(57) **CLAIM**

The ornamental design for an earphones with charging case, as shown and described.

DESCRIPTION

FIG. 1 is an exploded perspective view of an earphones with charging case showing my new design;

FIG. 2 is a front, right and top perspective view of the earphones with charging case shown in a closed configuration;

FIG. 3 is a rear, left and bottom perspective view thereof; FIG. 4 is a front, right and top perspective view of the earphones with charging case shown in an opened configuration;

FIG. 5 is a front view of the earphones with charging case shown in a closed configuration;

FIG. 6 is a rear view thereof;

FIG. 7 is a left side view thereof;

FIG. 8 is a right side view thereof;

FIG. 9 is a top plan view thereof;

FIG. 10 is a bottom plan view thereof;

FIG. 11 is a front, right and top perspective view of an earphones of the earphones with charging case shown separately to show aspects of the design that are not visible when combined;

FIG. 12 is a rear, left and bottom perspective view thereof;

FIG. 13 is a front view thereof;

FIG. 14 is a rear view thereof;

FIG. 15 is a left side view thereof;

FIG. 16 is a right side view thereof;

FIG. 17 is a top plan view thereof; and,

FIG. 18 is a bottom plan view thereof.

The broken lines shown in the drawings illustrate portions of the earphones with charging case that form no part of the claimed design.
